[57]

CLAIM

The ornamental design for a tool handle with holder, as shown and described.

DESCRIPTION

FIG. 1 illustrates a front perspective view of a tool handle with holder;
 FIG. 2 illustrates a front elevation view thereof;
 FIG. 3 illustrates a back elevation view thereof;
 FIG. 4 illustrates a right side elevation view thereof;
 FIG. 5 illustrates a left side elevation view thereof;
 FIG. 6 illustrates a top plan view thereof;
 FIG. 7 illustrates a bottom plan view thereof; and,
 FIG. 8 illustrates a back perspective view thereof.

UNITED STATES PATENT AND TRADEMARK OFFICE
CERTIFICATE OF CORRECTION

PATENT NO. : Des. 435,415

DATED : December 26, 2000

INVENTOR(S) : Johnson et al.

It is certified that error appears in the above-identified patent and that said Letters Patent is hereby correct as shown below:

On the front page, under heading [63], line 3, replace the date "Jun. 17, 1995" with --Jun. 7, 1995--.

Signed and Sealed this
First Day of May, 2001

Attest:

NICHOLAS P. GODICI

Attesting Officer

Acting Director of the United States Patent and Trademark Office
